UNITED STATES PATENT OFFICE

ARTHUR L. COLTON, OF MILWAUKEE, WISCONSIN.

DEVICE FOR HOLDING AND FILING LETTERS, BLANKS, AND OTHER PAPERS.

SPECIFICATION forming part of Letters Patent No. 339,859, dated April 13, 1886

Application filed February 6, 1886. Serial No. 190,998. (No model.)

To all whom it may concern:

Be it known that I, ARTHUR L. COLTON, of Milwaukee, in the county of Milwaukee, and in the State of Wisconsin, have invented certain new and useful Improvements in Devices for Holding and Filing Blanks, Letters, and other Papers; and I do hereby declare that the following is a full, clear, and exact description thereof.

10 My invention relates to devices for holding and filing blanks, letters, drawings, &c.; and it consists in certain peculiarities of construction, as will be hereinafter described with reference to the accompanying drawings, in
15 which—

Figure 1 represents a perspective view of my invention; Fig. 2, a detail perspective view of one of the sliding frames; Fig. 3, a similar view, partly broken away; Fig. 4, a vertical 20 longitudinal section of the cabinet with the sliding frame drawn out; Fig. 5, a transverse section on line $x-x$, Fig. 4, with the sliding board and frame closed in; Fig. 6, a detail view of one of the division plates or frames; 25 and Fig. 7, a transverse section on line $y-y$, Fig. 4, looking toward the rear.

Referring by letter to the drawings, A represents a suitable cabinet divided into compartments B, these latter being all of equal 30 or odd sizes, as circumstances may require. Each of the compartments B has a portion of its bottom a provided with a central groove, b , that forms a guide for the depending lip c of a stop, C, that is secured to the rear end of 35 a sliding board, D, the latter operating in grooves d , cut in the sides of the vertical parts E of the cabinet, and the forward movement of this sliding board is limited by the lip c coming in contact with the ungrooved portion 40 of the bottom a . The sliding board D is provided upon its upper face with a central rib, f , and groove g , the rib engaging a groove, h , upon the under face of a sliding frame, F, and acting as a stop, against which comes the lower 45 end of a vertical latch, i , that is guided in the groove g , said latch being connected to the rear vertical piece, k , of the sliding frame so as to be vertically operative. The rib f of the sliding board and groove h of the frame F 50 are preferably dovetailed, and the relative arrangement of the parts permits said frame to

be drawn out entirely clear of the cabinet, thereby facilitating access to its contents.

Pivotaly connected to the vertical pieces k 55 k' are skeleton clamping-frames G G, said frames being crossed at their front and rear ends in such a manner as to open out in opposite directions.

Upon the inner side of the front vertical piece, k' , of the sliding frame are guide-flanges 60 m for a friction-block, n , centrally secured upon a pin, o . To the pin o are connected the lower ends of links p , the upper ends of these links being united to arms r , that project up from the clamping-frames G G. 65

To the inner side of the vertical piece k' is secured a vertically-operative spring-plate, H, having ratchet-arms $s s$, that engage lugs t , projecting from the forward ends of the clamping-frames, thereby permitting said 70 frames to be firmly retained in any position to which they may be opened. The horizontal piece or bottom of the sliding frame is provided with transverse grooves v for rods I, that are secured to and come flush with the upper 75 face of said bottom. The rods I are designed to engage eyes z , depending from division-frames K, that serve to keep separate differing blanks or papers that may be filed away in the sliding frame F. The division-frames may be 80 simply skeleton in form, or, if desirable, covered by paper or cloth, as shown in Fig. 6.

Retained between the division-plates I show a series of envelopes, L, that are intended to be alphabetically or numerically arranged for 85 the reception of letters or other papers, and to facilitate access to any particular envelope the division-frames may be multiplied so that each two thereof will divide a certain number of said envelopes from the others in the set. 90

To further facilitate the selection of any particular envelope or envelopes the division-frames may be suitably lettered or numbered to correspond.

Each sliding frame F is intended to be provided with a suitable pull, M. 95

In the operation of my invention the frame F is drawn out until the latch i abuts against the rib f on the sliding board D, when the latter comes into action, and is drawn out with 100 said frame until the depending lip c of the stop C is brought into contact with the un-

grooved portion of the compartment-bottom *a*. By this operation the sliding frame and contents are brought out clear of the cabinet. The spring-plate *H* is now drawn up and 5 the clamping-frames disengaged from the ratchet-arms *s s* of said plate. This operation allows the clamping-frames to open out any desirable distance to permit of access to the contents of the sliding frame.

10 By the peculiar arrangement and operation of the clamping-frames *G G*, the horizontal rods *t t* thereof that come upon the same relative side of the frame *F* are always in the same vertical plane, no matter to what degree they 15 may be opened.

To disengage the sliding frame from the board *D*, it is only necessary to raise the vertical latch-plate *i* so as to bring the latter out of contact with the rib *f* on said board. When 20 the sliding frame *F* is pushed in, it comes against the upwardly-projecting lip *c* of the stop *C*, thus carrying the board *D* in at the same time, the back of the cabinet acting as a stop to limit the rearward movement.

25 Having thus fully described my invention, what I claim as new, and desire to secure by Letters Patent, is—

1. The frame for holding blanks, letters, &c., consisting of a horizontal bottom piece 30 and vertical end pieces, in combination with clamping-frames and a vertical plate having ratchet-arms adapted to engage lugs on said clamp-frames, as set forth.

2. The frame for holding blanks, letters, &c., consisting of a horizontal bottom and vertical end pieces, clamping-frames crossing each 35 other and pivoted to said vertical parts, and a vertical spring-plate having ratchet-arms adapted to engage lugs on the clamping-frames,

in combination with links operatively connecting 40 said clamping-frames, and a pin carrying a friction-block operative in vertical guides, as set forth.

3. The frame for holding blanks, letters, &c., consisting of a horizontal bottom and vertical end pieces, in combination with pivotally-adjustable clamp-frames and a series of division-frames operatively connected to said bottom piece, as set forth.

4. The frame consisting of a horizontal bottom piece and vertical end pieces, one of the latter provided with vertical guides, in combination with clamp-frames pivotally connected to said end pieces and provided with upwardly-extended arms, a friction-block operative in the vertical guides, links having their respective ends pivotally connected to the friction-block and to the arms of the clamp-frames, and a vertical spring-plate having ratchet-arms adapted to engage lugs on said 55 clamp-frames, as set forth.

5. The combination, with the frame *F*, having the groove *h* and end pieces, *k k*, and the paper-clamping devices, substantially as described, upon said frame, of the sliding base 60 *D*, having the rib *f* and stop *C*, the fixed base *a*, having the groove *b*, and the sliding catch *i*, all constructed and arranged substantially as and for the purposes set forth.

In testimony that I claim the foregoing I have hereunto set my hand, at Milwaukee, in the county of Milwaukee and State of Wisconsin, in the presence of two witnesses.

ARTHUR L. COLTON.
